UNITED STATES PATENT OFFICE.

ALFRED BRUCE BROWN, OF CALDWELL, NEW JERSEY, ASSIGNOR TO WESTERN ELECTRIC COMPANY, INCORPORATED, OF NEW YORK, N. Y., A CORPORATION OF NEW YORK.

MACHINE FRAMEWORK.

Original application filed April 4, 1924, Serial No. 704,149. Divided and this application filed December 7, 1925. Serial No. 73,690.

This invention relates to machine frameworks, and more particularly to improvements in frameworks of hydraulic extruding presses.

5 This application is a division of my co-pending application, Serial No. 704,149, filed April 4, 1924.

Various ways of anchoring the columns of the framework to the cap of an extruding 10 press and to lugs on the hydraulic cylinder thereof, are employed. For instance, the ends of the columns may be threaded and then anchored to the cap and lugs by means of large nuts; or the columns may be made 15 with integral bolt-head ends and the bolt-heads "hooked over" the corner of the cap by inserting the column in a U-shaped aperture in the corner of the cap, this same construction being employed in securing the 20 lower ends of the columns to the cylinder. When employing the first mentioned means it is very difficult to obtain the same tension on each one of the columns due to movement between the nut and the bolt threads.

25 The latter mentioned type is sometimes insufficiently rigid, and since the face of the bolt-head of the column is not seated throughout, foreign matter gradually seeps in at the unengaged side between the column 30 and its seat, allowing corrosion and causing an unseating of the seated members.

The object of this invention is to increase the rigidity and durability of machine frameworks.

35 According to one embodiment of the invention, in the production of the improved framework columns are employed having a bolt-head construction, the bolt-head at either end of the column being integral 40 therewith. Apertures in the four corners of the cap and in the lugs on the hydraulic cylinder are slightly larger than the bolt-head of the columns. Each column is extended through one of the four apertures in 45 the cap and the aperture in one of the lugs having flanged portions are then placed on the hydraulic cylinder. Split sleeves having flanged portions are then placed around the ends of the columns, and the 50 columns bearing the split sleeves are drawn back through the apertures in the cap and lugs until the flanged portions of the sleeves

seat themselves on the outside faces of the cap and lugs. Split nuts are then inserted around threaded portions of the columns and 55 the two sections of the split nuts being held together by suitable means, the nuts are drawn up tightly against the inside face of the cap and lugs, so as to prevent an unseating of the column from its ground seat on 60 the upper face of the cap and lower face of the lugs on the hydraulic cylinder.

The invention will be more fully understood from the following detailed description taken with the accompanying drawings, 65 in which

Fig. 1 is a front elevational view of a 70 press of the type employed for extruding lead in which the improved framework is utilized;

Fig. 2 is a fragmentary vertical sectional view taken on the line 2—2 of Fig. 1, and

Fig. 3 is a fragmentary sectional view 75 taken on the line 3—3 of Fig. 2, looking in the direction of the arrows.

Referring to the drawings, the invention is disclosed as applied to an extruding press which comprises a hydraulic cylinder 10 and a ram 11, slidably mounted in the hydraulic cylinder. Integral with the cylinder 10 are 80 apertured lugs 12—12, the function of which will be described more in detail hereinafter. The ram 11 carries a die block 13, and an extruding cylinder 16, said die block having an upper portion 14 and a lower portion 15, 85 respectively. Means (not shown) is provided for raising the ram 11 carrying the cylinder 16 into a position wherein a plunger 17 may enter the cylinder. Continued upward movement of the ram 11 will cause 90 the plunger 17 to displace any matter such as lead which may be contained in the cylinder. The plunger 17 depends from a cap 18 which is secured in spaced relation with respect to the hydraulic cylinder 10 by means 95 of four columns 19—19, opposite ends of which are attached to the cap 18 and the lugs 12 by means of split flanged sleeves 20, split nuts 21 and collars 22. The manner in which the split sleeve, split nut and collars 100 are employed will be more fully explained hereinafter.

The four columns 19 need be only approximately of the same length measuring from

the two inside faces of the column heads. Four apertures in the cap 18 and corresponding apertures in the lugs 12 are employed with flanged sleeves 20, nuts 21 and collars 22 for anchoring the four columns to the cap 18 and cylinder 10. The flanged sleeves 20 are ground to fit snugly against the inner face of the head of the column 19 and the opposite face of said flange 20 is ground to fit snugly against the outside face of the cap 18 or the lug 12. The thickness of the flanged sleeves 20 can be varied to compensate for difference in lengths of columns 19 so that the effective length of the columns 15 will be exactly the same. The sleeve portion of the flanged sleeve 20 is made to fit snugly between the column 19 and the walls of the aperture in the cap 18 or lug 12. There is consequently no play of the column in the 20 apertures in the cap and lugs.

The span between the several columns on account of the positive anchoring method and spacing method may be made exactly the same and the cap 18 consequently may 25 be positioned exactly at right angles to the axis of the hydraulic cylinder. Since adjacent parts are ground to produce a perfect seat the possibility of foreign matter seeping in and unseating the column is very 30 slight, particularly since engaged parts are at all times held in a rigid position. It is possible also when this construction is used to employ shims for the purpose of compensating for irregularities.

35 The framework is assembled by first placing the collars 22 over the heads of the columns 19, inserting one head of each column 19 through an aperture in the cap 18, and the other end of each column through a 40 corresponding aperture in a lug 12 on the cylinder 10. One of the split sleeves 20 is then placed around each end of the column with the flanged portion thereof adjacent to the column head, and the columns bearing 45 the flanged sleeves are then drawn back until their flanged portions rest upon the outside faces of the cap and lugs and the heads of each column rest on the faces of the flanges adjacent to them. The split 50 nuts 21 are then placed in position on threaded portions of the columns 19. The collars 22 are placed over the split nuts 21 and said 55 split nuts bearing the collars 22 drawn up tightly against the inside faces of the cap 18 and lugs 12.

The improved framework is not limited to use in extruding presses, as it may be em-

ployed wherever a heavy strong framework is required.

What is claimed is:

60 1. In a machine framework, a column having integral bolt-head ends, spaced members associated therewith and having apertures for receiving the column, and means engaging the apertures for providing a circular seat for the bolt-head ends of the columns on the spaced members.

65 2. In a machine framework, a column having an integral bolt-head end, a member associated therewith and having an aperture for receiving the column, and an annular abutting member engaging the aperture and designed to provide a circular seat for the bolt-head end of the column on the member.

70 3. In a machine framework, a column having an integral bolt-head end, a member associated therewith, and a split sleeve designed to encircle the column and provide a circular seat for the bolt-head end of the column.

75 4. In an extruding press framework, a column having an annular projection, a cap having an aperture for receiving the column, and means engaging the aperture for providing a circular supporting surface for said annular projection on said cap.

80 5. In an extruding press framework, a column having bolt-head ends, a cap and a split flanged sleeve adapted to form a supporting surface for the bolt-head ends of said column on said cap.

85 6. In an extruding press framework, a column, a cap having an aperture, and a split sleeve adapted to rigidly support said column in the aperture in said cap.

90 7. In an extruding press framework, a column having integral bolt-head ends, a cap, a member disposed therefrom, a plurality of split flanged sleeves, and means for utilizing said split flanged sleeves for rigidly and accurately positioning said cap in relationship to said member.

95 8. In an extruding press framework, a column having bolt-head ends, a cap, a member, said cap and said member having apertures for receiving the column, and means cooperating with said column for rigidly and accurately positioning said cap in relationship to said member, said means including members engaging the apertures in the cap and the first mentioned member.

100 In witness whereof I hereunto subscribe my name, this 25th day of November A. D., 1925.

ALFRED BRUCE BROWN.
